(57) **CLAIM**

I claim the ornamental design for three-dimensional presidential plaque, as shown and described.

DESCRIPTION

FIG. 1 is a perspective view of a three-dimensional presidential plaque, showing my new design;

FIG. 2 is a front elevational view thereof;

FIG. 3 is a left-side elevational view thereof, the right-side elevational view, top plan view, and bottom plan view all being a mirror image thereof; and,

FIG. 4 is a rear elevational view thereof.

The broken lines showing a plaque stand in FIG. 1 are included for the purpose of illustrating the invention in use, and form no part of the claimed design.
